UNITED STATES PATENT OFFICE.

RAYMOND FISHER, OF PHILADELPHIA, PENNSYLVANIA, ASSIGNOR TO JACOB K. ALTEMUS, OF PHILADELPHIA, PENNSYLVANIA.

AUTOMATIC STOP FOR WINDING-MACHINES.

1,216,557.

Specification of Letters Patent. Patented Feb. 20, 1917.

Application filed February 18, 1916. Serial No. 79,066.

To all whom it may concern:

Be it known that I, RAYMOND FISHER, a citizen of the United States, residing at Philadelphia, in the county of Philadelphia and 5 State of Pennsylvania, have invented certain new and useful Improvements in Automatic Stops for Winding-Machines, of which the following is a specification.

The invention relates to automatic stops 10 for winding machines and is illustrated as being applied to a yarn winding machine of the type shown in Patent #1,120,438 issued to Brooks. The primary object of the invention is to provide means for preventing the gain movement when the yarn breaks, as 15 will be hereinafter pointed out.

Reference will be had to the accompanying drawings forming a part of this specification and wherein like numerals of reference 20 designate corresponding parts throughout the several views, in which;

Figure 1 is a side elevation of yarn winding mechanism including the present improvements,

25 Fig. 2 is a plan or top view of the same,

Fig. 3 is a plan or top view of a fragment of Fig. 2 and showing the parts in the inoperative position, and Fig. 4 is a diagram illustrating the laying of the yarn.

30 Referring to the drawing, 2 is the winding spindle which may have imparted to it constant or variable rotary motion and 3 is the builder rail which reciprocates up and down and carries with it the builder screw 35 4, bracket 12, and spring pressed pawl 13 which intermittently causes partial rotation of the ratchet wheel 15 each time the builder rail 3 reaches the lower limits of its downward movements. Through the medium of suitable gearing as disclosed in the said Brooks 40 patent, the gain shaft 19 has similar rotative movements imparted to it from the said ratchet wheel 15. Splined on this shaft 19 and longitudinally movable therealong is a 45 spur-gear 24 for driving the gain nut-gear 25 through means to be described. Collars 26 and 27 on opposite sides of the gear 24 at all times overlap the gain nut-gear 25 and cause the spur-gear 24 to travel with said 50 gain nut-gear 25. On the gain nut-gear 25 is pivotally mounted an arm 29 held by spring 30 in engagement with the threads of the builder screw to cause the gain-nut-gear when it is rotated to climb said builder

screw, said arm 29 being disengageable with 55 the builder screw threads manually to permit the gain nut-gear to be lowered when it is desired to start a new bobbin.

As in the Brooks patent, the gain nut-gear 25 has a depending hub on the lower extremity of which lock nuts 33 are placed and upon the hub and held between said lock nuts and the gain nut-gear is a ring 34 provided with three arms 35, 36 and 37. A guide rod 38 projects upwardly from the 60 builder rail in parallel relation with the builder screw. The said arm 36 mounts the 65 yarn guide arm 40, and the arm 37 mounts another yarn guide and also a tension device 42. The yarn passes through the yarn guide 70 41, tension device 42 and yarn guide 40 to the bobbin on the spindle 2.

The stop lever 22 with its cams 11 and 21 act, which is also true of the parts thus far described, the same as in the said Brooks 75 patent.

Referring to the present improvements, reference will first be had to the diagram in Fig. 4. The heavy lines indicate double yarn layers termed layer sets, each layer set 80 comprising an up or progressive layer indicated by arrow P, and down or retrogressive layer indicated by arrow R. The yarn guide traverses from elevation A to elevation A'; B to B'; C to C'; and so on 85 to completion of the bobbin. After it has gone from elevation A to elevation A' and back to elevation A, the gain mechanism causes the gain nut-gear 25 to turn on the builder screw 4 and to step up the yarn 90 guide so that the next traverse begins at B, the arrow G between elevation A and elevation B indicating the gain movement; this same gain movement is carried on throughout the whole bobbin. The layers and layer sets are conical and are nested, the diagram showing the effect on only one side of the conical layers, the effect being the same elsewhere through any point in the layers or layer sets.

100 In the Brooks device, if the yarn breaks, the spindle continues its rotation, the yarn guide its traverse, and if the operator is not in constant attendance to cut the machine off almost immediately the yarn breaks, the 105 gain nut-gear will have carried the yarn guide considerably beyond where it was when the yarn broke. In other words, if the

gain is in position for the laying of layers between elevations A and A' when the yarn breaks, if the machine is not immediately stopped, upon the yarn being repaired, the laying will be in the path upon resumption between the elevations C and C' or even a higher path, instead of taking up somewhere either in the progressive or retroprogressive layers occurring between elevations A and 10 A' where the yarn was winding when the break occurred. The result in most cases is that the package wound is worthless because of its unevenness and consequent imperfect binding of the yarn coils relatively to each 15 other.

With the present improvements, it is immaterial whether or not the operator is strictly in attendance to throw the lever 22 and thereby cut off the movements of the 20 machine. If the yarn breaks, the gain mechanism will automatically be thrown out of operation and the continued traverse movement of the yarn guide and rotating of the spindle will be without effect upon the package being wound. For example, if the layer 25 set between elevations A and A' is being wound and the break occurs at point S in the progressive layer, the spindle will continue rotation and the traverse motion or 30 reciprocation of the builder rail will continue, both without any influence upon the package, but on the other hand, the gain movement ceases immediately and automatically, and, until the attendant is free to give his 35 attention to repair of the yarn, the mechanism running along in the manner described can do no harm. Upon repair of the yarn, the laying will be resumed somewhere, say at point J, in the progressive or retroprogressive layers of the layer set which was 40 being laid (between elevations A and A'), when the break occurred. The effect upon the package will be negligible whether the laying resumes at the same point in the 45 traverse at which the break occurred, so long at it resumes in the same or immediately succeeding layer without material intervening gain. In some cases, the gain movement 50 might take place just as the break occurs, but even then the laying must resume with the immediately succeeding layer, though of the next succeeding layer set, and this is immaterial in affecting the product.

The improvements which produce stopping of this gain movement consists in providing the free end of the arm 35 with a transverse elongated opening 50 producing stops 51 and 52 connected at their outer portions by portion 53, the last mentioned being 55 unessential as the end of the arm 35 could merely be forked by employing only the stops 51 and 52 separated a distance greater than the diameter of the embraced rod 38. The gain shaft 19 of the Brooks machine is

reset so that its spur-gear 24 is at all times 65 out of mesh with the gain nut-gear 25, and this resetting of said shaft necessitates modification of the cam portion 21 of the Brooks lever 22, and slight changes otherwise not pertinent to the subject matter herein 70 claimed. The arm 35 is provided with a right-angular extension 54 on which is journaled a gear or pinion 55 constantly enmeshed with the gain nut-gear and adapted to be enmeshed with the driving gear 24. 75

In operation, the yarn passing through guide 41, tension 42 and guide 40 to the bobbin on the spindle 2, causes the yarn guide 40 to be pulled toward the bobbin and the stop 51 to engage with one side of the 80 bar 38 and the gear or pinion 55 to enmesh with the driving spur-gear 24. Upon the yarn breaking, there is nothing to longer pull the parts to the position just described, consequently the driving spur-gear 24 moving outwardly at the meshing point with gear or pinion 55 throws the said gear or pinion 55 in the direction of the arrow A in Fig. 2 to the Fig. 3 position so that the stop 52 engages with the rod 38. Upon repair of the yarn, resumed feed thereof will cause the gear or pinion 55 to move in the direction of the arrow B in Fig. 3 to again enmesh the pinion 55 with the driving gear 24. As long as the yarn is not feeding 90 through the guides 40 and 41 and the tension device 42, or in other words not pulling the parts so that they assume the positions in Fig. 2, the parts will be in the Fig. 95 3 position and because of the pinion 55 not imparting driving motion from the gear 24 to the gain nut-gear 25, the latter cannot progress along the builder screw and consequently as related to the gain movement, the yarn will resume laying substantially 100 at the same point where it left off. Of course, as in Brooks, the stop lever 22 is available to the operator or attendant and this is thrown to cut off the spindle and 105 traverse movements while the yarn is being 110 repaired.

What is claimed:

1. In a yarn winding machine, a builder screw, a driving gear, a nut-gear mounted thereon, a pivotally mounted arm carried by the nut-gear, a yarn guide on the arm and movable toward and from the spindle, and means movable with said arm to engage and disengage the nut-gear from driving connection with the driving gear. 115

2. In a yarn winding machine, a winding spindle, a pair of parallel members, one of said members being threaded, a nut mounted on the threaded member, an arm pivotally mounted on one of said members and being carried with the nut, a yarn guide on said arm and being movable by the yarn toward the spindle, a driving device, and a gear on 120 125

said arm in constant driving connection with said nut and in driving connection with said device only when the yarn guide is moved by the yarn in the direction of the 5 spindle.

3. In a yarn winding machine, a winding spindle, a rod, a builder screw rod parallel therewith, a nut-gear on the builder screw rod, means for operating said nut-gear, a 10 yarn guide arm carried by the nut-gear and pivotally mounted, the pivotal axis thereof being coincident with the axis of the builder screw rod, said arm having stop portions residing on opposite sides of the first mentioned rod and spaced apart a distance greater than the diameter of the said rod, a 15 gear carried by said arm and in mesh with the nut-gear, and a driving gear on the arm

movable into and out of driving relation with said operating means for the nut-gear. 20

4. In a winding machine, a rod, means thereon adapted to progress therewith, a swinging arm carried by said means, a driving gear, a gear on said arm in driving connection with said first means and movable 25 with said arm into and out of mesh with said driving gear, means on said arm whereby the tension of the yarn will swing said arm in one direction to hold said gears enmeshed, the relation of said gears being 30 such that upon release of the arm due to breakage of the yarn the drive gear will force the arm gear out of mesh therewith.

In testimony whereof I affix my signature.

RAYMOND FISHER.
